(57) **CLAIM**

The ornamental design for an accessory bracket as shown and described.

DESCRIPTION

FIG. 1 is a perspective view in a condition of use of the accessory bracket for allowing angular support bracing of a separate pivoting member showing my new design;

FIG. 2 is a right side elevation view thereof;

FIG. 3 is a front side elevation view thereof;

FIG. 4 is a left side elevation view thereof;

FIG. 5 is a rear side elevation view thereof;

FIG. 6 is a top plan view thereof; and,

FIG. 7 is a bottom plan view thereof.

The broken lines shown in the drawings illustrate portions of the article. The additional broken lines shown in FIG. 1 show environment. All broken lines shown form no part of the claimed design.
